UNITED STATES PATENT OFFICE.

STEVEN A. RICE, OF SAN FRANCISCO, CALIFORNIA.

ILLUMINATED SIGN.

Application filed August 10, 1925. Serial No. 49,229.

This invention relates to illuminated signs of the type adapted to be used for automobile license plates, advertising purposes, etc., and the primary object of the invention is 5 to provide an improved device of this character.

As is well known, automobile license plates are formed in different colors each year, whereby to easily distinguish the new plates 10 from the old. It is also desirable in advertising and other signs to occasionally change the color scheme. My invention provides an improved illuminated sign device wherein the color scheme can be easily changed as 15 desired. It is another object of my invention, therefore, to provide an improved device of this character which can be very cheaply and easily manufactured, will be neater and more attractive in use, and the 20 color scheme of which can be readily and easily changed at will.

With the above and other objects in view, as will hereinafter appear, my invention consists in the features of construction and 25 operation set forth in the following specification and illustrated in the accompanying drawing. In such drawing annexed hereto and forming a part of this specification, I have shown certain embodiments of my invention, but it will be understood that the invention can be otherwise embodied and that the drawing is not to be construed as defining or limiting the scope of the invention, the claims appended to this specification 30 being relied upon for that purpose.

Referring to the figures of the drawing—

Fig. 1 is a front elevation of an automobile license plate and holder constructed in accordance with my invention.

40 Fig. 2 is a plan view thereof partially broken away.

Fig. 3 is a vertical sectional view therethrough, on line III—III of Fig. 1.

45 Fig. 4 is an enlarged fragmentary rear view of one end of the front plate thereof.

Fig. 5 is a front view of an advertising sign constructed in accordance with my invention.

50 Referring first to Figs. 1 and 4 of the drawing, 1 indicates a comparatively shallow sheet metal box open only at the front and made from a single piece of metal. In constructing this box the sheet is formed with projecting wings of such a shape that when 55 folded together the same form the edges and front border 2 about the front opening. The

front of the top edge 3 is slotted at 4 to receive a front plate 5 therein, and a U-shaped strip 6 is mounted in each end of the box and forms a guideway between the front border 2 and such strip to receive and hold the front plate in position.

60 The front plate 5 has characters stencil cut therethrough, as the license number illustrated in Fig. 1. The top edge is bent over at 7 and a slit 8 is provided in an ear 9 thereof for receiving a staple 10. The staple is adapted to receive a padlock for locking the plate against removal. The front surface of the plate 5 can be painted any color desired and the stenciled characters or numbers can be made to appear of any other color desired by the means now to be described.

65 I provide a colored backing plate 11 for the front 5, the backing plate being mounted directly on the rear of the front plate as illustrated. Preferably, I provide flanges 12 on the edges of the front plate for holding the backing plate thereto. These flanges 70 are bent over the rear face of the front plate as illustrated in Fig. 4 in a manner to hold the backing plate at the edges thereof. These flanges 12 in connection with the top 7 serve to hold the backing plate securely 75 in place against the rear face of the front plate. It will be obvious that the construction is extremely simple, very cheap to manufacture, and most efficient in operation.

80 A pair of electric light sockets 13 are mounted in the bottom edge of the box 1 in a manner adapted to conveniently receive electrical connections thereto and bulbs 14 therein. When the bulbs are lighted the stenciled characters appear very brilliantly 85 through the backing plate 11. This plate 90 can be of any material desired, the same, however, preferably being of light weight, thin, translucent and non-inflammable. It 95 will be understood that when the license plate is to be changed a new plate of any color desired. The backing plate 11 can be 100 easily removed and one of another color substituted therefor, as will be understood.

105 In Fig. 5 I have shown my invention adapted to an advertising sign. The construction of the body or box 15 is substantially the same as box 1 above described. Any stencil as the word "Cyclo", can be cut 110

through the front plate 16. An electrical circuit for the lights is supplied through the cord 17 and the sign can be hung from a chain 18. It is intended that this sign shall be hung in a window or other conspicuous place and the same will show very brilliantly in any color scheme desired.

It is believed that the construction, operation, and various advantages of my invention will be obvious from the above description. The device produced is simple and cheap to manufacture and its arrangement provides all the features desired in such a device in a most efficient manner.

Having thus described my invention, what I claim and desire to secure by Letters Patent is:

1. An illuminated sign comprising the combination of a comparatively shallow sheet metal box open at the front, an electric light therein, a removable metal front plate having characters stencil cut therethrough, a colored backing plate carried by the stenciled plate at the rear thereof, flanges integral with the edges of the stenciled plate and bent backward therefrom in a manner to receive and to hold the backing plate, and a

pair of independent members extending respectively along the ends of the box therein and spaced from the front marginal edge 30 of the box in a manner providing a pair of vertical slideways for receiving the ends of the combined front plate and backing plate thereinto.

2. An illuminated sign comprising the 35 combination of a comparatively shallow sheet metal box open at the front, an electric light therein, a removable metal front plate having characters stencil cut therethrough, a colored backing plate carried by the 40 stenciled plate at the rear thereof, flanges integral with the bottom and side edges of the stenciled plate and bent backward therefrom in a manner to receive and hold the 45 backing plate, means at the end of the box and at the front side thereof providing slideways for receiving the combined front plate and backing plate thereinto, a rearwardly 50 projecting integral flange on the top edge of the front plate, and means co-operating therewith for locking the front plate in its inserted position in the box.
